UNITED STATES PATENT OFFICE.

EMIL L. OPPERMANN, OF ROCHESTER, NEW YORK, ASSIGNOR TO PRECISE MANUFACTURING CORPORATION, OF ROCHESTER, NEW YORK, A CORPORATION OF NEW YORK.

ELECTRIC SWITCH.

Application filed June 26, 1925. Serial No. 39,681.

My present invention relates to electric switches and more particularly to a switch which is adapted to automatically cut off the current to an electric machine when the latter becomes overloaded and it has for its object to provide a simple and serviceable switch particularly adapted for use on such mechanisms as domestic washing machines which are usually operated by mechanically unskilled persons. The improvements are directed in part toward the provision of a simple arrangement whereby the automatic circuit breaker is prevented from operating while the motor is being started and there is an unavoidable overload thereon. To these and other ends the invention resides in certain improvements and combinations of parts all as will be hereinafter more fully described, the novel features being pointed out in the claims at the end of the specification.

In the drawings:

Figure 1 is a front view of a switch casing containing a switch constructed in accordance with and illustrating one embodiment of my invention;

Figure 2 is a side view thereof;

Figures 3 and 4 are views similar to Figure 1 but with the casing in section to disclose the operating parts and showing the latter in different positions.

Figure 5 is an enlarged section through the short circuiting device taken on the line 5—5 of Figure 4;

Figure 6 is a view similar to Figures 3 and 4 but with the casing shell removed;

Figure 7 is a side view of the switch mechanism with the casing in section and showing the opposite side from that shown in Figure 2;

Figure 8 is an enlarged section on the line 8—8 of Figure 4;

Figure 9 is a similar fragmentary section taken on the line 9—9 of Figure 6 and

Figure 10 is an enlarged section taken on the line 10—10 of Figure 6.

Similar reference numerals throughout the several views indicate the same parts.

The invention is disclosed in the present instance, by way of illustration, as embodied in an automatic switch apparatus of a variety particularly suitable for controlling the circuit of a relatively small motor, such as employed for operating washing machines and the like, comprising preferably, a base

10 in the form of a block of insulating material to which is fitted a protective casing 11, as shown for enclosing its forward side on which are mounted the operating parts.

Referring more especially to Figures 3 and 4, the switch portion proper includes a pair of spaced and insulated contact means or clips 13 preferably of resilient conducting strips of metal secured to the base and having their ends curved downwardly toward the base and thence upwardly again in the form of a loop as shown. The ends are preferably provided with contact plates 14 of substantial thickness and wearing qualities. These contacts are secured by means of the usual nut and screw device indicated at 15, the outer strip or a conducting extension thereof, being provided with a binding post 16 for connection with one terminal of the circuit to be controlled. A movable switch contact 17 is provided as hereafter described for connecting the cooperating contacts 14 and thereby closing the circuit.

Referring now more particularly to the automatic means for opening the switch when the circuit exceeds a predetermined safe limit, the inner switch contact 14 has its securing screw connected by means of a wire 18 through a slot 19, Figure 10, in the back of the base with one terminal of the coil of a solenoid 20 having a U-shaped laminated core piece 21 extended exteriorly longitudinally of the coil as shown at 22. The other terminal 23 of the coil is connected with a clip 24 on the base having an outwardly and downwardly looped light spring contact member 25 (Figures 3 and 9) secured thereto. The opposite end of the clip is provided with a binding post 26 for connection with the other side of the controlled circuit. It is thus apparent that when the contacts 14 are connected by the movable switch part 17, the circuit extends from the outer to the inner of these contacts 14, thence through solenoid 20 to clip 24 and back to the line so that the solenoid is included in the controlled circuit. Associated with the solenoid and actuated thereby is a mechanism for automatically effecting movement of switch part 17 to open the circuit when the current becomes excessive as described below.

The movable switch part 17 is preferably in the form of a shoe, Figures 4 and 5, pivotally and thus yieldably supported as at 110

27 on a clip 28 carried by and insulated from a switch lever 29 pivoted at 30 on a post 31 carried by the base. The shoe or contact 17 is thus adapted to yieldably accommodate 5 itself to engagement with both contacts 14 in the closed position of the switch, (Figure 4). Lever 29 is formed with a recess or notch 32 in its lower edge, Figure 8, for engagement with the recessed portion 33 of 10 a push button 34 guided and sliding longitudinally in a bearing 35 on the base. Manual depression of this button therefore, serves to swing lever 29 on its pivot to engage the contact means and close the switch against 15 the action of a spring 36 having one end adjustably connected as at 37^a with the opposite arm of the lever 29 as more particularly described hereafter.

Means are provided for retaining the 20 switch in closed position until opened under the action of spring 36 either by the overload solenoid 20 already described or by manual means explained hereafter. Such means comprises an angular portion 37 on 25 the other end of switch lever 29 which portion has an extended lug 38 struck laterally to provide at 39 a seat for engagement with the end 40 of a latching lever 41 pivotally supported at 42 on the extension 22 of the 30 solenoid core. The other end 43 of the latching lever is positioned and adapted to function as an armature for actuation by solenoid 20 which pulls this end of the lever in a direction to move its opposite end 40 out of 35 latching engagement with the switch lever. Spring 36 has its outer end connected as at 44 with the latching lever so that this single spring serves economically and compactly to not only move the switch lever to open 40 position but also the latching lever into engagement with the switch lever in opposition to the force of the solenoid. Manual means are also provided for swinging the latching lever to release the switch lever for 45 movement by the spring comprising a push button 45 extending through an opening in the casing into attachment with a leaf spring 46 fixed on the casing, the parts being so positioned that the depression of the 50 button carries its inner end into engagement with the latching lever and trips the latter to open the switch.

Attached to the clip portion 29 of the switch lever and hence in electrical contact 55 with it and the shoe 17 is a light spring arm 28^a. When the switch is open and the device is in the normal position of Figures 3 and 9, the spring contact member 25 is expanded and tends to push the button 34 outwardly 60 by engagement with the end thereof. The spring arm 28^a extends through the loop of the contact member but in this normal position is out of contact with it as clearly shown in Figure 9. When the button 34 is 65 pressed in to move the switch arm to closed

position it first moves contact 25 to the depressed position of Figure 8 in which it picks up spring arm 28^a and makes electrical contact therewith. This serves to short circuit the solenoid during such engagement and release the latching lever 44. Upon further inward movement of the button a shoulder 34^a thereon picks up the switch lever 29 and moves the switch element 17 into engagement with the yielding contacts 13 and 14 so that the circuit is closed with the solenoid shorted out. This permits the motor to assume the overload necessary in starting without being cut off.

In the meantime the switch lever is positioned for latching by the latching lever as the deenergizing of the solenoid releases the latching lever for movement by its spring to latching position. Upon releasing the button 34 it is thrust outwardly by the spring contact member 25 as shown in Figure 9 and contact with the spring arm 28^a is broken as shown in Figures 6 and 9 so that the coil is again connected in circuit. The button has the lost motion connection with the switch lever as shown to permit this release of the contact member 25 while the switch is still closed. To summarize the operation, with the device connected in the circuit to be controlled, depression of finger piece or button 34 first short circuits the solenoid and then closes the switch and moves the switch lever into latching engagement with the latching lever. The shorting contact is maintained in this way sufficiently long for the motor to get under way before the latching lever can be influenced to immediately release the switch. Should the current in the circuit exceed a predetermined value, its energizing effect upon the solenoid causes the latter to attract the corresponding end of the latching lever, the opposite end of which releases the switch lever which is quickly moved by spring 36 to open the circuit. Or if this safety feature does not come into operation, button 45 is depressed when it is desired to break the circuit and the latching lever is thus manually actuated to release the switch lever for movement to opened position.

I claim as my invention:

1. In an apparatus of the class described, the combination of a circuit controlling switch automatically occupying a given one of a plurality of positions to which the switch is movable, retaining means for holding the switch against said automatic movement, a device included in circuit with the switch for automatically actuating said retaining means to release the switch, an element arranged for inclusion in the circuit and having connections for short circuiting said device, and means for progressively operating the short circuiting element and then the switch.

2. In an apparatus of the class described, the combination of a circuit controlling switch automatically occupying a given one of a plurality of positions to which the switch is movable, a pivoted latching lever for holding the switch against said automatic movement, solenoid means included in circuit with the switch for automatically actuating said lever to release the switch, and contact means closed prior to a closing movement of the switch and having connections for short circuiting said solenoid means.
3. In an apparatus of the class described, the combination of a circuit controlling switch automatically occupying a given one of a plurality of positions to which the switch is movable, a pivoted latching lever for holding the switch closed against said automatic movement, solenoid means included in circuit with the switch for automatically actuating said lever to release the switch, a pair of contacts disengaged in each of said switch positions and engaged temporarily prior to the movement of the switch to closed position, and connections for short circuiting said solenoid means by the engagement of said contacts.
4. In an apparatus of the class described, the combination of a circuit controlling switch manually movable to closed position, manually operable latch means for holding said switch in closed position, solenoid means for moving said latch means to switch releasing position, spring means for moving said switch to open position and said latch means to switch retaining position, contact means for short circuiting said solenoid means and a manually operable member for actuating said short circuiting means and thereafter closing the switch.
5. In an apparatus of the class described, the combination of a circuit controlling switch manually movable to closed position, manually operable latch means for holding said switch in closed position, solenoid means for moving said latch means to switch releasing position, spring means for moving said switch to open position and said latch means to switch retaining position, contact means for short circuiting said solenoid means embodying a spring contact member and a connection from the switch member arranged in the path of said contact member, and operating means adapted to first bring the spring contact member and the switch member connection into contact to complete the short circuit and to thereafter close the switch.
6. In an apparatus of the class described, the combination of a circuit controlling switch manually movable to closed position, manually operable latch means for holding said switch in closed position, solenoid means for moving said latch means to switch releasing position, spring means for moving said switch to open position and said latch means to switch retaining position, contact means for short circuiting said solenoid means embodying a spring contact member and a connection from the switch member arranged in the path of said contact member, and operating means adapted to first bring the spring contact member and the switch member connection into contact to complete the short circuit and to thereafter close the switch, said operating means embodying a movable device having a lost motion connection with the switch.

EMIL L. OPPERMAN.
